APPARATUS FOR THE AMALGAMATION
OF ORESClaude Joseph François Phily, dit de Phily,
Le Genest, FranceApplication July 26, 1934, Serial No. 737,078
In France March 19, 1934

9 Claims. (Cl. 209—205)

The present invention concerns an apparatus particularly intended for the extraction of amalgamable metals, such as gold, contained in ores, said extraction being obtained even without the usual assistance of water and with a higher efficiency than with the processes hitherto known.

Apparatus may consequently be used for the extraction of metals existing at a free state into ores, which are previously crushed when necessary and both process and apparatus may also be used for the collection of any amalgamable silver contained into roasted ores or in any other case in which amalgamation may be used.

The main feature of the present invention consists in utilizing, in order to obtain the amalgamation, the surface tension or surface viscosity phenomena well known in physics under the name of Pasteur's tests. Should the surface of a bath of mercury be covered with fine sandstone and a rod be vertically dipped into the bath, the sand will disappear as if it was drawn by the rod, and will subsequently return at the surface upon removal of the rod.

I have ascertained that whatever may be the thickness of the layer of fine sand covering the mercury, the thickness of sand drawn by the rod remains at the least value corresponding to the size of its grains, and is continuous as long as the rod sinks and as sand is left upon the surface.

According to the invention the main feature of the apparatus intended to carry out the present process is constituted by elements to which is imparted a continuous motion, such as sheet metals for instance, the superficial extension of which is as large as possible. Such elements dip into a bath of mercury, thus drawing the sand according to the surface viscosity or surface tension phenomena mentioned above.

An arrangement which is particularly advantageous is as follows: the entrainment of the sand ore is produced by the rotary motion around their axis of one or more cylinders provided with flat blades placed perpendicularly with respect to the axis of the cylinder and sunk up to a given depth into a bath of mercury: the sand is poured at the surface of the mercury from one side of the cylinder, and is drawn into the mercury by means of the blades which carry it under the cylinder; the sand comes up again at the surface at the other side, after being exhausted.

According to a further feature of the invention, the rotary motion imparted to the cylinder should be slow: the blades being rotary bodies, in such case there is no stirring of the mass. I have ascertained that in such conditions the amalgam

which is richer in gold accumulates at the base of the container, separation taking place by gravity.

It will be advantageous to place the one after the other two or more exhaustion cylinders.

The metal which would not come into contact with the mercury, owing to the arrangement of the grains of sand, during the passage under the first cylinder, will be recovered in the subsequent ones.

In order to reduce the amount of mercury used, it will be advantageous to design the tank containing the bath in the form of a half-cylinder concentrical to the blade carrying cylinder; at the bottom of said tank is provided a discharge cock enabling the continuous or discontinuous extraction of the rich amalgam thus formed.

In order that the invention may be fully understood, it will be now described with reference to the accompanying drawing in which:

Figure 1 is a diagrammatic sectional view of an apparatus according to the present invention.

Figure 2 is a diagrammatic view in horizontal section corresponding to the line II—II of Figure 1.

Figure 3 is a diagrammatic view in vertical axial section of an apparatus provided with two elements in series, according to the invention.

Figure 4 is a diagrammatic view of a three-elements apparatus according to the invention.

The apparatus shown in Figures 1 and 2 is constituted by an iron cylinder 1 whose lateral surface is provided with blades 2 of iron or like material resistant mercury, such as aluminium, wood, glass or the like. Said blades are arranged into planes which are perpendicular to the axis of the cylinder, the said arrangement providing a large area of contact for relatively reduced overall dimensions of the cylinder.

The blade carrying cylinder 1 revolves slowly and in a continuous direction around its fixed horizontal axis, in a semi-cylindrical trough 3 filled with mercury.

The inlet zone of the blades into the mercury is supplied with ore sieved through fine meshes. The grains entrained by the blades or sticking to them owing to surface tension are automatically released at the discharge end of the device, as soon as immersion is finished, and since they accumulate in this place they soon overflow, upon 50 a weir 4. During the immersion they leave their amalgamable particles into the bath.

The easy recovery of the dissolved gold is based upon the principle which has been acknowledged by the inventor that a liquid alloy of two metals

of sufficiently different densities, such as mercury and gold and of contents which are still far from the value corresponding to their solid alloy at the temperature of the bath, tends to concentrate in state of rest into the part which facilitates the production of a solid solution, either for the system mercury-gold at the lower part or for the system mercury-silver at the surface.

The gold amalgamating apparatus is consequently provided at the bottom of the trough, with an adjustable opening 5 for the discharge of the auriferous mercury. The discharge performs continuously drop after drop, in order to avoid that a too long period of rest, may allow the concentration to take place up to a solid solution content (about 45 per cent gold), thus obstructing the opening 5 (in the silver amalgamating apparatus a similar device is provided adjacent to the free surface).

20 The mercury thus removed is replaced at regular periods of time, by fresh mercury which is added in the trough 3. The amount of mercury added will be higher than the amount discharged through the opening 5. The excess of fresh mercury will cause a discharge of the soiled mercury rising at the surface, by means of an overflow (not shown). This discharge from the surface permits the renewal of the active surface of the mercury and the collection of the light amalgams 25 such as that of silver.

The liquid amalgam thus collected is either once more concentrated by sedimentation, in order to be subsequently treated by means of a chamois leather or directly subjected to said 30 treatment.

The amalgam is clean since being collected far from its surface, it cannot contain any of the usual impurities, sand or pyrites which are so difficult to eliminate when collection is accomplished upon the usual amalgamation tables.

40 The apparatus may be constituted by a single unit consisting of a cylinder-trough or as shown in Figure 3, by two or three elements in series, each of the subsequent element collecting in its turn, for its entrainment, the sand delivered by the preceding one. For some ores of the gauge of sands the arrangement in series is liable to increase the efficiency by increasing the period of immersion and changing from one element to another the arrangement of the entrained layers.

50 Though this is not generally necessary, it is possible to activate the amalgamation of some ores by leading an electric current through the bath or by the addition of an activating agent, such as sodium.

55 The process may be used either as a dry process or as a wet process, provided that in both cases the fluidity or easy displacement of the solid particles the ones with respect to the others, is secured for their entrainment. The intermediate state, i. e. a given amount of humidity which would agglomerate the sand to be treated would also prevent entrainment.

The advantage of the dry process is that a 65 higher output is required for equal size of apparatus, the action of surface tension being more powerful. The advantage of the wet process is that a minor amount of mercury is entrained in the sand being discharged. The choice of the 70 process will depend upon local conditions.

In the case of the wet process an advantageous arrangement consists to partially or totally drown with water the apparatus above the surface of the mercury. The immersion into water of the 75 upper part of the rotary surface has two advan-

tages, i. e. first to secure in a constant manner a sufficient dilution of the pulp in the inlet zones and second to accomplish a permanent cleaning of the revolving surface. The sands fall into a chamber which is also submerged with water and are then carried to the separator by means of a 5 paternoster 6. Figure 4 shows a water amalgamating apparatus, with three cylinders provided with interleaved blades.

Before being finally discarded, the discharged 10 sands are carried to a dry or wet separator in order to recover the mercury which they may contain. The mercury thus recovered may continuously be brought back to the apparatus.

The advantages of an apparatus of the above 15 mentioned type are the following: first that it is possible to treat auriferous ores in regions deprived from water, second to supply a higher efficiency of amalgamation compared to the usual wet processes, due to the direct contact between 20 gold and mercury and owing to the fact that there is no loss of the finest particles entrained as "floating gold" in the usual treatments with water current.

Further, the gold amalgam thus obtained is 25 clean and the straining washing operations are dispensed with. The gold and silver amalgams are thus recovered separately and thus are not mixed, as in the case of the methods now in use.

The operation is continuous and necessitates no 30 stopping for collecting or cleaning; it enables to reduce labor costs.

The overall dimensions are considerably reduced for the same output.

Finally the precautions against thefts are 25 easier, the amalgam being collected only in one place for the whole factory.

Having now particularly described and ascertained the nature of my invention and in what manner the same is to be performed, I declare that 40 what I claim is:

1. Apparatus for extracting precious metals from ores in a container by amalgamation, comprising at least one trough filled with mercury, a shaft, means for rotating said shaft continuously, 45 a drum mounted on said shaft so as to be partially immersed in the mercury bath, blades fixed on said drum and disposed in planes perpendicular to the axis of said drum, the said drum and the said blades being formed of a material which is 50 not wetted by mercury, and means for feeding the ores between the drum, the blades, and the trough from the side of the drum, and the blades penetrating into the mercury bath.

2. Apparatus for extracting precious metals 55 from ores in a container by amalgamation, comprising at least one trough filled with mercury, a shaft, means for rotating said shaft continuously, a drum mounted on said shaft so as to be partially immersed in the mercury bath, blades 60 fixed on said drum and disposed in planes perpendicular to the axis of said drum, the said drum and the said blades being formed of a material which is not wetted by mercury, means for feeding the ores between the drum, the blades, and the trough from the side of the drum, and the blades penetrating into the mercury bath, and a weir disposed at the side of the drum opposite to said feeding means, the blades leaving the mercury bath adjacent said weir and evacuating the spent 70 ores from said bath onto said weir.

3. Apparatus for extracting precious metals from ores in a container by amalgamation, comprising at least one trough filled with mercury, a shaft, means for rotating said shaft continuously, 75

5 a drum mounted on said shaft so as to be partially immersed in the mercury bath, blades fixed on said drum and disposed in planes perpendicular to the axis of said drum, the said drum and the said blades being formed of a material which is not wetted by mercury, means for feeding the ores between the drum, the blades, and the trough from the side of the drum, and the blades penetrating into the mercury bath, and means disposed at the bottom of the trough for evacuating whatever gold amalgam is formed.

10 4. Apparatus for extracting precious metals from ores in a container by amalgamation, comprising at least one trough filled with mercury, a shaft, means for rotating said shaft continuously, a drum mounted on said shaft so as to be partially immersed in the mercury bath, blades fixed on said drum and disposed in planes perpendicular to the axis of said drum, the said drum and the said blades being formed of a material which is not wetted by mercury, means for feeding the ores between the drum, the blades, and the trough from the side of the drum, and the blades penetrating into the mercury bath, means at the lowest 15 point in said trough for evacuating whatever gold amalgam that is formed, and a stopcock associated with said last-mentioned means, the said stopcock being opened at an extent whereby there can be evacuated in a continuous manner a quantity 20 of amalgam substantially equal to the average quantity of amalgam which is produced.

25 5. Apparatus for extracting precious metals from ores in a container by amalgamation, comprising a plurality of troughs disposed side by side in tandem, each trough containing a filling of mercury, a shaft in each trough, means for imparting a continuous rotational movement to said shafts, a drum mounted on each shaft and adapted to be partially immersed in its corresponding 30 mercury bath, a plurality of circular plates disposed about and concentric with the drum, the said plates extending perpendicularly to the axis of said drum, the said drum and plates being formed of a material not wetted by the mercury, the plates of one of the drums extending between the plates of the neighboring drum, and means 35 for feeding the ores between the first drum, the plates thereof, and its trough, from the side of the said drum, the plates penetrating into the mercury bath.

40 6. Apparatus for extracting precious metals from ores in a container by amalgamation, comprising a plurality of troughs disposed side by side in tandem, each trough containing a filling 45 of mercury, a shaft in each trough, means for imparting a continuous rotational movement to said shafts, a drum mounted on each shaft and adapted to be partially immersed in its corresponding mercury bath, a plurality of circular plates disposed about and concentric with the

drum, the said plates extending perpendicularly to the axis of said drum, the said drum and plates being formed of a material not wetted by the mercury, the plates of one of the drums extending between the plates of the neighboring drum, 5 means for feeding the ores between the first drum, the plates thereof, and its trough, from the side of the said drum, the plates penetrating into the mercury bath, means disposed at the bottom of each trough for removing whatever gold amalgams that are formed, and conduits interconnecting the said last-mentioned means at a common point.

7. Apparatus for extracting precious metals from ores in a container by amalgamation, comprising at least one trough filled with mercury, a shaft, means for rotating said shaft continuously, a drum mounted on said shaft so as to be partially immersed in the mercury bath, blades fixed on said drum and disposed in planes perpendicular to the axis of said drum, the said drum and the said blades being formed of a material which is not wetted by mercury, means for feeding the ores between the drum, the blades, and the trough from the side of the drum, and the blades penetrating into the mercury bath, means for supplying fresh mercury to said trough, and an overflow means for removing, outside of the trough, materials riding on the surface of the mercury bath.

30 8. Apparatus for extracting precious metals from ores in a container by amalgamation, comprising at least one trough filled with mercury, a shaft, means for rotating said shaft continuously, a drum mounted on said shaft so as to be partially immersed in the mercury bath, blades fixed on said drum and disposed in planes perpendicular to the axis of said drum, the said drum and the said blades being formed of a material which is not wetted by mercury, means for feeding the 35 ores between the drum, the blades, and the trough from the side of the drum, and the blades penetrating into the mercury bath, means for supplying fresh mercury to said trough, and an overflow means for removing from the trough the spent 40 mercury and any silver amalgam which may be formed.

9. Apparatus for the extraction of precious metals from ores by amalgamation, comprising a trough filled with mercury, a shaft, means for turning said shaft in continuous manner, blades solid with said shaft and disposed perpendicularly thereto, and means for introducing the ore into the trough from that side of the principal axis of the trough on which the said blades penetrate 55 into the bath of mercury, the said shaft and blades being formed of a material which is not wetted by mercury.

CLAUDE JOSEPH FRANCOIS
PHILY, DIT DE PHILY. 60
